DESIGN FOR A CHILD'S ROCKER

Lawrence Hollander, Detroit, Mich., assignor to
Stamping Products & Mfg. Co., Detroit, Mich.,
a corporation of Michigan

Application August 26, 1946, Serial No. 132,858

Term of patent 3½ years

(Cl. D15—6)

To all whom it may concern:

Be it known that Lawrence Hollander, a citizen of the United States of America and a resident of Detroit, in the county of Wayne and State of Michigan, has invented a certain new, original, and ornamental Design for a Child's Rocker, of which the following is a specification, reference being had to the accompanying drawing forming a part thereof, and wherein:

Fig. 1 is a perspective view of a child's rocker embodying my new design;

Fig. 2 is a side elevational view thereof on an enlarged scale; and

Fig. 3 is a plan view thereof.

I claim:

The ornamental design for a child's rocker, substantially as shown.

LAWRENCE HOLLANDER.
